Application November 21, 1952, Serial No. 321,837

2 Claims. (Cl. 201—48)

This invention relates to devices for indicating the intake manifold pressure of internal combustion engines and more particularly to an intake manifold pressure actuated device for visually indicating whether an internal combustion engine is operating within a predetermined portion of its power range.

It is among the objects of the invention to provide an improved indicating mechanism which can be mounted adjacent an internal combustion engine and actuated by the intake manifold pressure of the engine to advise the operator of the engine whether or not the engine is operating in a predetermined desirable portion of its power range, so that the operator can, if necessary, effect a more efficient operation of the engine by readjusting the throttle setting, shifting the change speed transmission or placing the overdrive mechanism into or out of operation in the case of an automotive vehicle, boat or aircraft engine, or by such other means as may be available to him; which includes a visual signal element, such as an electric lamp, and intake manifold pressure operated mechanism, including a variable resistance device connected into the lamp circuit, effective to cause the lamp to be brightly illuminated when the engine is operating outside of a predetermined desirable portion of its power range and to be dimly illuminated or extinguished when the engine is operating within the desirable portion of its power range; which is adjustable for different engines and different operating conditions; which can be connected to an engine with no material modification of the engine construction; and which is simple and durable in construction, economical to manufacture, easy to install, and effective in operation.

Other objects and advantages will become apparent from a consideration of the following description and the appended claims in conjunction with the accompanying drawing wherein:

Figure 1 is a side elevational view of manifold pressure indicating mechanism illustrative of the invention;

Figure 2 is a medial longitudinal cross sectional view of the mechanism illustrated in Figure 1;

Figure 3 is an end elevational view of the mechanism illustrated in Figure 1 looking at the left-hand end of the mechanism as illustrated in this figure; and

Figure 4 is a diagrammatic view of the indicating mechanism showing the application thereof to the intake manifold of an internal combustion engine.

With continued reference to the drawing, and particularly to Figure 4, the numeral 10 generally indicates an internal combustion engine having an intake manifold 11 provided with a charge heating chamber 12 and to which a carburetor 13 is operatively connected.

It is well known that the power output of internal combustion engines, such as are commonly used for the propulsion of automotive vehicles, boats and aircraft and for stationary power plants, is directly proportional to the operating speed of the engine and the engine intake manifold pressure and that, when the manifold pressure is in the lower portion of the range of manifold pressures,

2

the engine is then operating at its highest efficiency for the current operating speed of the engine. In accordance with the present invention, a portion of the range of intake manifold pressure within the lower portion of the range is selected as the limited range of intake manifold pressures providing the best engine economy at various engine speeds and indicating mechanism is provided to inform the driver of the associated vehicle or operator of the engine when the engine is operating at manifold pressures above the selected lower portion of the range of manifold pressures consistent with efficient engine operation.

The indicating mechanism comprises an expandable chamber device, generally indicated at 15, which is illustrated as comprising a hollow housing 16 of rigid construction consisting of a pair of bell shaped parts 17 and 18 secured together with their open ends in mutually registering relationship by suitable means, such as screws 19 extending through registering apertures in superposed annular flanges 20 and 21 provided on the housing parts 17 and 18 respectively, at the open ends of these housing parts.

A flexible diaphragm 22 extends transversely of the interior of the housing 16 and is marginally clamped between the housing flanges 20 and 21.

The housing 16 is provided with a centrally disposed hollow tubular guideway 23 extending therefrom in a direction away from the housing part 17 and at its end remote from the housing part 18 the guideway 23 is provided with a combined valve and tube fitting 24 having a bore communicating with the interior of the tubular guide 23 and an adjustable valve screw 26 intersecting the bore to variably restrict the area of the bore. The fitting 24 is connected by a suitable conduit 26 to a fitting 26' secured in an aperture in the engine intake manifold 11, so that the interior of the tubular guide formation 23 is in communication with the interior of the intake manifold.

The housing part 17 is provided with a centrally located aperture 28 and a shaft 29 extends slidably through the aperture 28 and through a centrally disposed aperture 30 in the diaphragm 22. The portion of the shaft 29 extending through the diaphragm is reduced in diameter and externally screw threaded, as indicated at 31, and clamping nuts 32 and 33 are threaded onto the shaft at respectively opposite sides of the diaphragm and secure the diaphragm to the shaft for movement of the shaft by the diaphragm when the diaphragm is moved by pressure variations in the portion of the housing 16 at the side of the diaphragm adjacent the tubular guide formation 23. The diametrically reduced portion of the shaft 29 extends beyond the diaphragm 22 and is slidably received in an aperture 34 provided in a guide spider 35 mounted in the tubular guide formation 23.

As its end disposed outwardly of the housing part 17 the shaft 29 is externally screw threaded, as indicated at 36, and a washer 37 receives the shaft 38 at the inner end of the screw threaded end portion 36 of the shaft. A compression spring 38 surrounds the shaft 29 between the washer 37 and the adjacent surface of the housing part 17, and a nut 39 is threaded onto the screw threaded portion 36 of the shaft and bears against the washer 37 at the side of the washer remote from the spring 38.

A movable contact carrier in the form of an angle arm 40 has two legs disposed substantially perpendicular to each other and one of these legs is provided with an aperture receiving the shaft 29 at the side of the nut 39 remote from the washer 37. A second nut 41 is threaded onto the screw threaded end portion 36 of the shaft 29 and bears against the side of the one leg of the angle arm 40 remote from the nut 39 to clamp the angle arm between the nuts 39 and 40 and thus rigidly secure the angle arm on the shaft 29.

An angle bracket 42 is secured at one end to the housing part 17 and projects outwardly from this housing part in spaced and substantially parallel relationship to the portion of the shaft 29 projecting out of the same housing part.

An elongated resistance coil 43 is mounted on the angle bracket 42 and extends longitudinally of the angle bracket and a movable contact 44 is carried by the other leg of the angle arm 40 in position to engage the resistance coil 43.

When the intake manifold pressure is within a predetermined portion near the lower end of the pressure range, the diaphragm 22 is drawn toward the tubular guide formation 23, as illustrated in Figure 2, moving the shaft 29 against the force of spring 38 in a direction toward the combined valve and tube fitting 24. This positions the movable contact 44 off of the coil 43, as illustrated in Figure 2, or on the end of the coil nearest the housing 16. As the manifold pressure increases, the spring 38 moves the shaft 39 in a direction to move the movable contact along the coil 43 from the end of the coil nearest the housing 17 toward the opposite end of the resistance coil.

The engine 10 is provided with a suitable source of electrical energy, such as the storage battery 45; and is also provided with an ignition controlling switch 46; one side of which is connected to the battery 45 by an electrical conductor 47. A conductor 48 leads from the other side of the switch 46 to the engine ignition system and another conductor 49 also leads from the same side of the switch as that from which the conductor 48 extends to the movable contact 44. A conductor 50 leads from the end of the resistance coil 43 remote from the housing 16 to a lamp bulb socket 51 mounted at a location readily visible to the operator of the engine or driver of the associated vehicle, as on the instrument board of a vehicle; and the other side of the battery 45 is provided with a ground connection 52, the side of the battery 45 remote from the conductor 47 being grounded, as indicated at 53. A lamp bulb 55 is mounted in the socket 51.

When the movable contact 44 is at the end of the coil 43 nearest the housing 16, the lamp circuit is broken and the lamp is extinguished; and when this movable contact is on the end of the resistance coil nearest the housing, the lamp is only dimly illuminated, since the lamp circuit then includes all, or most of the resistance coil. Thus, when the pressure in the intake manifold vacuum is low, the lamp is only dimly illuminated or completely extinguished. As the pressure in the intake manifold rises and the movable contact 44 is moved along the resistance coil 43 in a direction away from the housing 16, less and less of the resistance coil is included in the lamp circuit and the lamp is progressively more brilliantly illuminated as the movable contact 44 is moved from the end of the resistance coil nearest the housing 17 to the end of the resistance coil furthest from the housing. As the lamp becomes more brilliantly illuminated, the operator or driver of the associated vehicle is warned that the engine intake manifold pressure has risen above the predetermined lower portion of the intake manifold pressure range and that the operating efficiency of the engine has accordingly decreased and that suitable measures should be taken to restore the operating efficiency of the engine.

The invention may be embodied in other specific forms without departing from the spirit or essential characteristics thereof. The present embodiment is, therefore, to be considered in all respects as illustrative and not re-

strictive, the scope of the invention being indicated by the appended claims rather than by the foregoing description, and all changes which come within the meaning and range of equivalency of the claims are, therefore, intended to be embraced therein.

What is claimed is:

1. A pressure indicating device comprising a hollow housing consisting of a pair of bell shaped parts having their open ends in mutually registering relationship, a diaphragm interposed between and secured to the open ends of said parts, a hollow tubular guideway exteriorly of one of said parts and having one end secured to said one part, a combined valve and tube fitting connected in communication with the other end of said guideway adapted to be connected to a source of pressure, a guide spider mounted within said guideway adjacent said one end thereof, a shaft extending through said pair of parts and diaphragm and slidably supported in said spider and the adjacent wall portion of the other of said parts and having one end inwardly of and adjacent the other end of said guideway and having a portion adjacent the other end projecting exteriorly of the other of said parts, said diaphragm being secured to said shaft for movement therewith, a bracket positioned exteriorly of said other part and extending parallel to the projecting end portion of said shaft and carried by said other part; an angle bracket having one leg fixed to the projecting end portion of said shaft and having the other leg parallel to said bracket, a resistance coil on said bracket; and a movable contact carried by said one leg of said angle bracket and engageable with said coil.

2. A pressure indicating device comprising a hollow housing consisting of a pair of bell shaped parts having their open ends in mutually registering relationship, a diaphragm interposed between and secured to the open ends of said parts, a hollow tubular guideway exteriorly of one of said parts and having one end secured to said one part, a combined valve and tube fitting connected in communication with the other end of said guideway adapted to be connected to a source of pressure, a guide spider mounted within said guideway adjacent said one end thereof, a shaft extending through said pair of parts and diaphragm and slidably supported in said spider and the adjacent wall portion of the other of said parts and having one end inwardly of and adjacent the other end of said guideway and having a portion adjacent the other end projecting exteriorly of the other of said parts, said diaphragm being secured to said shaft for movement therewith, a bracket positioned exteriorly of said other part and extending parallel to the projecting end portion of said shaft and carried by said other part; an angle bracket having one leg fixed to the projecting end portion of said shaft and having the other leg parallel to said bracket, a resistance coil on said bracket, a movable contact carried by said one leg of said angle bracket and engageable with said coil, and spring means operatively connected to the projecting end portion of said shaft for biasing said one end of said shaft away from said fitting.
